UNITED STATES PATENT OFFICE

165,077

PIANO BENCH

Belle A. Kandarian, Fresno, Calif.

Application April 16, 1951, Serial No. 15,038

Term of patent 14 years

(Cl. D15—8)

To all whom it may concern:

Be it known that I, Belle A. Kandarian, a citizen of the United States, residing at 920 R Street, Fresno, county of Fresno, State of California, have invented a new, original, and ornamental Design for Piano Bench, of which the following is a specification, reference being had to the accompanying drawing, forming a part hereof.

Fig. 1 is a front perspective view of a piano bench, illustrating my new design.

Fig. 2 is a top plan view of the piano bench.

Fig. 3 is a rear elevation thereof.

Fig. 4 is an end elevation looking at the left end as viewed in Fig. 1.

I claim:

The ornamental design for a piano bench, as shown.

BELLE A. KANDARIAN.
